UNITED STATES PATENT OFFICE

2,164,664

AUTOMATIC SHOE DISPLAY DEVICE

Wilbur H. Parkison, Chattanooga, Tenn.

Application June 7, 1938, Serial No. 212,278

1 Claim. (Cl. 312—134)

This invention relates to display devices, particularly of the type adapted for shoes.

One object of the invention is to provide an improved traveling display device for shoes.

5 Another object of the invention is to provide an improved device for the traveling display of a plurality of rows of articles, such as shoes, so as to obtain the effect of depth in viewing the articles, and to permit the articles to be readily observed from different angles.

Another object of the invention is to provide an improved display device having a plurality of offset traveling belts and a unitary illuminating means therefor.

15 Another object of the invention is to construct an improved cabinet for the stationary and traveling belt display of articles, such as shoes.

Another object of the invention is to furnish a belt, drive and cabinet arrangement for a traveling display device.

20 Another object of the invention is the provision of an improved traveling or endless belt display device having means for turning the articles carried by the belt to exhibit different views thereof.

25 Another object of the invention is to provide a traveling belt display device having improved means for securing shoes in different positions thereon according to the character or style of the shoes.

30 A further object of the invention is to furnish a display device of improved construction and arrangement, and having few and simple parts, and which is compact, neat and attractive in appearance, easy and convenient in operation, durable, reliable, and efficient in use.

35 Certain advantages of the invention are best exemplified when considered in relation to the display of shoes. Heretofore it has been the customary practice for the shoe salesman to take from stock and unbox many pairs of shoes in the endeavor to find a pair which would suit the customer in respect not only to fit, but also in relation to style, quality and price. In catering to ladies, the busy salesman usually finds himself with a large quantity of shoes lying around, which must be accurately reassembled in pairs, reboxed and put away in their appropriate places. With the present invention, the customers may 40 be comfortably seated and in a comparatively few moments conveniently and leisurely inspect all or a substantial part of the entire stock carried in the store. With the shoes properly tagged, the customer may make notations of the numbers and prices of the shoes, and thus come pre-

pared for quick sales service. Thus store space is conserved, as well as the time and energy of both salesman and customer. The latter will purchase with the satisfaction of having seen everything, and many sales will thus be consummated that would otherwise be lost. In actual use in a large store, the present display device has directly resulted in an actual substantial increase in the sale of shoes, over a large period of time. The invention aims to afford these advantages.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a perspective isometric view showing a device embodying the invention, with the shoe holding elements omitted.

Fig. 2 is a longitudinal sectional view of the device taken on line 2—2 of Fig. 3, showing some of the shoe holding elements and illustrating certain shoes as held thereby.

Fig. 3 is a vertical sectional view taken on the line 3—3 of Fig. 2, with the shoe holding elements omitted.

Fig. 4 is a vertical sectional view taken on the line 4—4 of Fig. 2, showing certain of the shoe holding elements.

Fig. 5 is a fragmentary plan view of the device showing the means for turning the shoes.

Fig. 6 is a bottom view of the belt showing an element of the turning means.

Fig. 7 is a view in end elevation with parts in section showing the shoe securing means.

Fig. 8 is a view in side elevation thereof with parts removed, and one of the parts shown in dot-dash lines.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is

submitted merely as showing the preferred exemplification of the invention.

Referring in detail to the drawing, 10 denotes a display device embodying the invention, and 5 which will be illustratively described herein in connection with the display of shoes. Said device 10 may comprise any suitable cabinet 11, which may have like front and rear walls 12, a bottom wall 13, and like end walls 14. Said casing may have a top opening closed by a plate of glass 15. A central longitudinal partition 16, 16a may divide the cabinet into two sections having like display means, so that only one of them need be described. Horizontal shelves or 10 walls 17, 18 may provide compartments 19 on opposite sides of the partition 16 for the stationary display of shoes. These compartments may be closed by glass plates or doors 20 slideable as in tracks 21 of the side walls 12. Vertical reinforcement walls 22 may extend from top to bottom of the cabinet, spaced inward of the end walls 14 to provide end walls for the compartments 19 and to provide upright end compartments 23 extending the full height and width of 15 the cabinet 11. These end compartments 23 may be bounded by inclined top corner walls 24 having glass windows 25 for the display compartments formed by the walls 26, 27. Mounted on the walls 17, in the compartments 23, between 20 the partition 16 and the windows 25 which confront the same along the side walls 12, are the upright wall elements 30, which may extend between the walls 22, for a purpose hereinafter described.

35 Mounted in the end compartments 23 are the upper and lower shafts 31, 32, and the shafts 33 are mounted in the compartments 23 to the rear of the walls 30. The shafts 31, 32 carry pulleys 34 for the endless belts 35, 36 which are disposed 40 side by side. The belt 35 is trained over the pulleys 37 carried by the shafts 31, and the belt 36 is trained over the pulleys 38 carried by the shafts 33. In one of the end compartments 23 are a pair of shafts 39 carrying the idler tensioning pulleys 40 for the belts 35, 36. Mounted 45 on one of the shafts 32 is a pulley or sprocket wheel 41 connected by a belt or chain 42 to a similar drive element 43, which is connected to any speed reducing means 44, driven by an electric motor 48. The motor and speed reducer units 50 may be disposed in an end compartment 23 as shown or in the central compartment 49 below the floor 18. It will now be apparent that the motor 48 drives four belts 35, 36 at equal speed 55 or at different speeds depending upon the pulley sizes. Hence the traveling display is operated at both sides of the central partition 16 simultaneously. It will be noted that the belt 35 has its lower run beneath the floor 18 and passing 60 through openings 50 in the walls 22, with the upper run of the belt passing through openings 51 in said walls, which openings are all of sufficient size for the passage therethrough of shoes carried by the belt. Likewise the belt 36 passes 65 through lower openings 50.

It will now be seen that the upper run of the belt 35 lies along the bottom of the window 28, and the upper run of the belt 36 lies along the upper edge of the wall element 30, with the belts 70 being thus partially concealed to afford a neat and attractive arrangement as shown in Fig. 1.

If illumination be desired, one or more lamps 53 may be disposed under a single reflector 54 which rests on the glass plate 15 so as to project light into both of the sections 29.

In order to mount the shoes in conformity with 5 the height of the heels thereof, each belt 35, 36 is provided with a series of spaced holders 55, each comprising an adjustable clamp 56 for clamping the sole of a shoe at opposite edges of the arch thereof. The clamp 56 may be vertically 10 and angularly settable, as by having a shank 57 having a slot 58 receiving a screw 59 which engages an anchor plate 60 secured to the belt. Hence the elevation of the clamp may be adjusted along the slot, and the angle of the clamp may 15 be adjusted by pivotal movement about the screw 59, to thus suit any style of shoe. By using a split spring washer 61 for the screw 59, the adjustment of the clamp may be frictionally easily effected. The plate 60 may also have an extension 62 to which a descriptive tag for the shoes 20 may be attached or clamped.

In order to permit the observer to obtain a direct front view as well as a side view of the shoes, in course of their travel, I provide means 25 for rotating or angularly moving or turning the shoes. For example, the holders 55 may each have a pin 63 journaled in the belt in any suitable manner to permit the holder 55 to be turned. Attached to the pin 63 is any suitable means for 30 causing angular motion, for instance, a pair of arms 64, 65 which project toward opposite edges of the belt for engagement with the respective cams 66, 67 disposed along the opposite edges of the belt and mounted on any suitable adjacent 35 parts of the cabinet as shown in Fig. 4. It will be noted that the cams are longitudinally spaced along the belt and that the arms 64, 65 are at an angle to each other, whereby the holder 55 is first turned in one direction and then reversed 40 to initial position as may be seen from Fig. 5. More specifically, the initial position of the holder is shown at *a* with the shoe extending longitudinally of the belt. As the belt travels toward the right, the projecting end of the arm 64 strikes 45 the cam 66 to turn the holder to the position indicated at *b*, thus affording a more direct view of the front of the shoe. This position is maintained at *c*. Due to the turning of the end of the arm 64, arm 65 now projects to strike the cam 67 50 causing the holder to return to its original position at *d*. This operation is automatic and can be effected by inexpensive means.

It will thus be seen that I have provided a device which fulfills the objects of the invention 55 and is well adapted for practical use.

I claim:

A display device including a cabinet having a plurality of endless traveling belts having article holding means, said belts having adjacent 60 runs at different elevations, said cabinet having a window confronting said runs of the belts, said cabinet having a vertical wall extending along and between said runs of the belts up to the upper belt to conceal the edges thereof, said cabinet 65 having a wall concealing the other portions of the belts, whereby only the upper runs of the belts are visible through said window, to appear like traveling floors for the articles, and means for driving the belts.

70 WILBUR H. PARKISON.
